UNITED STATES PATENT OFFICE.

HERMAN DOCK, OF PHILADELPHIA, PENNSYLVANIA.

EXPLOSIVE-ENGINE.

No. 831,044.

Specification of Letters Patent.

Patented Sept. 18, 1906.

Application filed November 6, 1903. Serial No. 180,005.

To all whom it may concern:

Be it known that I, HERMAN DOCK, a citizen of the United States, residing at Philadelphia, county of Philadelphia, and State of Pennsylvania, have invented a new and useful Improvement in Explosive-Engines, of which the following is a full, clear, and exact description, reference being had to the accompanying drawings, which form a part of this specification.

My invention has for its object certain improvements in the construction and mode of operation of explosive-engines, whereby the initial starting of the engine may be accomplished better and with more certainty.

In my improved engine, which forms the subject-matter of this invention, I initially connect the carbureter with air under pressure. There is thus admitted to the cylinder gas under pressure, so that the piston is forced forward on its first stroke by the normal expansion of the gas, and on the return stroke of the piston the exhaust-valve is operated by a supplemental cam to release a part of the compressed mixture, the remainder being recompressed by the return movement of the piston and fired when the piston is at or about the beginning of the next forward stroke. By this construction I start my engine automatically by the normal expansion of the gas and continue the starting impulse by the expansion of the gas due to ignition. After the engine has been started in this manner connection between the carbureter and the source of air under pressure is cut off and connection is made between air at atmospheric pressure and the carbureter, so that the engine continues to operate in the ordinary manner.

In the accompanying drawings I have shown an apparatus by which my improved method may be carried out.

Figure 1 shows an illustrative view, partially in section, of my invention. Fig. 2 is a top plan view, partially in section.

In the drawings, A is the source of pressure-supply, in this case shown as a pressure-tank.

B is the so-called "carbureter" of an explosive-engine—that is, a chamber in which the gas or vapor and air are admixed to form an explosive mixture.

C is a pipe leading from the carbureter B

to the cylinder D of the engine, having a suitable inlet-valve therein.

55

E is a pipe leading from the source of pressure-supply A, and F is a pipe leading from the atmosphere. These pipes E and F come together at the valve G, from which valve a pipe H leads to the carbureter. By turning this valve connection may be made either from the pipe E (from the pressure-supply) to the carbureter B or from the pipe F (atmosphere) to the carbureter.

I is the piston; J, the connecting-rod; K, the cranks; L, the crank-shaft; M, the exhaust-cam gears; N, the exhaust-cam; O, a supplemental or relief cam movable in and out of alignment with the exhaust-valve stem P by suitable means, such as a wheel Q. 70

R is the exhaust-valve controlling the port S from the cylinder to the exhaust T.

The gearing driving the main cam N is such that this cam operates the exhaust-valve at each second back stroke of the piston. The supplemental or relief cam O is so set that when in operative position it operates the exhaust-valve back strokes of the piston alternate to that of the cam N. 75

In carrying out my invention, in the initial starting of the engine the valve is turned, as shown in the drawings, to connect the pipe E with the carbureter, admitting gas under pressure to the cylinder, forcing the piston ahead on one forward stroke by normal expansion of the compressed charge. When the piston has moved forward under this pressure, the relief-cam O operates the exhaust-valve R, relieving some of the pressure. On the return stroke of the piston the remainder of the initial charge is recompressed and fired in the ordinary manner. After the engine has been started and attains sufficient momentum the supplemental cam I is moved out of action, the valve G is turned so as to connect the pipe F with the carbureter B, under which conditions the engine will continue its operation by drawing in a charge under atmospheric pressure and will operate in the usual way. 100

Having now fully described my invention, what I claim, and desire to protect by Letters Patent, is—

1. In an explosive-engine, in combination, a cylinder, a carbureter, connection between the carbureter and the cylinder, a source of

air-pressure supply, a pipe leading therefrom to the carbureter, a pipe leading from the atmosphere to the carbureter, and means to connect the carbureter with either the atmosphere or the air-pressure supply.

2. In combination, a cylinder, a carbureter, connection between the carbureter and the cylinder, a source of air-pressure supply, a pipe leading therefrom, a pipe leading to the atmosphere, and a valve adapted to connect the carbureter with either the air-pressure pipe or the pipe to the atmosphere.

3. In combination, a cylinder, a carbureter, connection between the carbureter and the cylinder, a source of air-pressure supply, and means to connect the carbureter with either the air-pressure supply or the atmosphere.

4. In an engine of the character described, 20 a cylinder, a piston therein, means for supplying a charge of explosive mixture under pressure to said cylinder to drive the piston on a forward stroke by normal expansion, an exhaust adapted to relieve a portion of said 25 charge near the end of said stroke, said piston on its return recompressing the balance

of said charge, means to ignite such recompressed charge at such point as to drive the piston ahead on its next forward stroke by expansion due to ignition.

5. In an engine of the character described, 30 a cylinder, a piston therein, means for supplying a charge of explosive mixture under pressure to said cylinder to drive the piston on the forward stroke by normal expansion, an exhaust adapted to relieve a portion of said charge near the end of said stroke, said piston on its return recompressing the balance 35 of said charge, means to ignite such recompressed charge at such point as to drive the piston ahead on its next forward stroke by expansion due to ignition, and means for cutting off the supply of compressed mixture and supplying an explosive mixture under atmospheric pressure.

40 In testimony of which invention I have hereunto set my hand, at Philadelphia, on this 28th day of October, 1903.

45 HERMAN DOCK.
